[57] CLAIM

The ornamental design for secretarial arm chair, substantially as shown.

DESCRIPTION

FIG. 1 is a perspective view of the chair of my design;
FIG. 2 is a front elevational view thereof;
FIG. 3 is a side elevational view thereof;
FIG. 4 is a rear elevational view thereof;
FIG. 5 is a top plan view thereof;
FIG. 6 is a bottom plan view thereof;
FIG. 7 is a generally rear perspective view thereof; and
FIG. 8 is a perspective view of an alternative embodiment of my design as shown in FIGS. 1—7 in which tufting buttons have been added.

FIG. 4.**FIG. 5.****FIG. 6.****FIG. 7.**

FIG. 8.
